UNITED STATES PATENT OFFICE

ANNA HOLMES, OF DALLAS, TEXAS

CONTAINER

Application filed September 11, 1930. Serial No. 481,307.

This invention relates to improvements in receptacles or containers having means for efficiently leveling material in a spoon or other instrument during withdrawal of the 5 same after receiving material from within the container.

A further object of this invention is the provision of an improved spoon leveling device of a relatively simple nature which may 10 be efficiently formed or placed within the upper portion of a container in a position which will not interfere with the ingress or egress of materials, and which will not interfere in any way with ordinary closing or opening of 15 the can, yet which may be utilized when desired for leveling of the contents of a spoon or the like as it is withdrawn from the receptacle or container.

A further object of this invention is the 20 provision of a device to facilitate the leveling of a teaspoonful or tablespoonful of material as it is withdrawn from a container, which cooperates in a relatively simple and efficient reinforcing and bracing relation 25 with the container.

Other objects and advantages of this invention will be apparent during the course of the following detailed description.

In the accompanying drawing, forming a 30 part of this specification, and wherein similar reference characters designate corresponding parts throughout the several views.

Figure 1 is a perspective view of the improved container, showing the closure lifted 35 from the body, with the material leveling device in position.

Figure 2 is a plan view of the open end of the container, showing the spoon leveling device in position.

Figure 3 is a fragmentary sectional view 40 showing the manner in which material in a spoon may be leveled as the spoonful of material is withdrawn from the container.

Figure 4 is an enlarged fragmentary sectional view taken transversely through the leveling blade.

In the drawing, wherein for the purpose of illustration is shown only a preferred embodiment of the invention, the letter A may 45 generally designate the container, which in-

cludes a body portion B having the leveling device C operatively placed therein in a manner which will not interfere with the efficient removal and placement of a closure D; the leveling device C being provided for the 55 purpose of leveling off the material within a spoon or other instrument E as the latter is withdrawn after receiving materials from the container.

The body B preferably comprises a cylindrical wall portion 11, of tin or other material, affixed in usual manner, having a bottom wall 12 crimped or secured thereto in any approved relationship. The upper end of the body B is open to the compartment 13 therein. Spaced below the top edge 14 of the body wall 11 is an annular bead or crimp 15, extending inwardly, which reinforces the container at the top.

The closure D is of inverted cup-shaped 70 type, including a top wall 17 having a depending annular skirt 16 which is adapted to frictionally receive the upper portion of the body wall 11 of the container A. This skirt 16 is provided with inwardly extending annular crimp or bead 18 against which the top edge 14 of the body wall 11 abuts to limit the downward position of the closure 75 D upon the can body B. This crimp also reinforces the closure.

The improved leveling device C is preferably constructed of a band of metal of relatively thin gauge material which is longitudinally doubled between the opposite longitudinal edges thereof, at an edge 20, 80 which is convex, and in fact is the leveling edge. The overlapping doubled portions 21 and 22 are of unequal widths, that is, the portion 21 is wider than the portion 22, as shown in the drawing. The ends of the leveling device C are transversely bent or turned at 30 with respect to the straight line of the body portion of the leveling device C, and are slightly arcuated and secured as by soldering or riveting or in any approved 85 manner to the inner periphery of the body wall 11 at the open top portion of the container body B, as shown in the drawing. The height or overall width of the leveling device C is equivalent to the straight line 90 100

dimension between the top edge 14 of the wall 11 and the bead 15, so that the attached ends 30 may be efficiently placed and secured in such manner that the top edge 35 of the leveling device lies flush with the top edge 14 of the cam body 11, as shown in the drawing. In this position the straight portion of the leveling device C lies truly diametrical across the open end of the compartment

10 of the can, for reinforcing and strengthening the neck portion of the container body B over which the closure D fits.

The container body B may be impressed with suitable indicia 40 designating the location from which the lid D is intended to be placed upon the container body B, so as to prevent distortion of the container body at the closure receiving neck thereof, for obvious reasons.

15 20 It is to be particularly noted that the leveling device C is relatively thin and will not prove to be an obstruction for either the ingress or egress of the total contents of the container A at any time. The leveling de-

25 vice does not interfere with the sanitary condition of the container. Furthermore, the leveling device is of sufficient height that the contents of the spoon or instrument E may be efficiently leveled without liability 30 of overspilling of the contents of the spoon back onto the spoon during a leveling operation, as would occur with the use of round or relatively narrow sections of material.

35 Various changes in the size, shape, and arrangement of parts may be made to the form of invention herein shown and described, without departing from the spirit of the invention or the scope of the claims.

I claim:

40 1. In a device of the class described the combination of a container having a detachable closure therefor, said closure including a flange adapted to telescope upon the exterior of the container, and a diametrically 45 disposed leveling and reinforcing member fixedly secured at its ends within the open end of the container, the container externally thereof having indicia designating an end of the member pertinent to the location at which 50 the cover should be started when placing upon the container.

2. A container having a compartment open at the top of the container, and a leveling blade of band-like material longitudinally 55 doubled upon itself and secured at its ends to the inner walls of the container in the open top thereof.

3. A container having a compartment open at the top of the container, a leveling blade 60 of band-like material longitudinally doubled upon itself and secured at its ends to the inner walls of the container in the open top thereof, so that the top edge of the blade lies flush with the top edge of the container.

65 4. A container having a compartment open

at the top of the container, a leveling blade of band-like material longitudinally doubled upon itself and secured at its ends to the inner walls of the container in the open top thereof, so that the top edge of the blade lies 70 flush with the top edge of the container, the downwardly facing edge of the blade being the edge at which the blade is doubled upon itself and being convex to provide a scraping edge.
